US00D605020S

(12) **United States Design Patent**
Martone et al.

(10) **Patent No.:** **US D605,020 S**
(45) **Date of Patent:** **** Dec. 1, 2009**

(54) **DEMOLITION TOOL**

(75) Inventors: **Joseph Martone**, Bristol, CT (US); **Eric Ranieri**, Besancon (FR)

1,114,837 A 10/1914 Wilson
1,465,009 A 8/1923 Wasseth
1,469,472 A 10/1923 Bangert
1,472,517 A 10/1923 Fry

(73) Assignee: **The Stanley Works**, New Britain, CT (US)

(Continued)

(**) Term: **14 Years**

CA 2296048 7/2007

(21) Appl. No.: **29/321,428**

(Continued)

(22) Filed: **Jul. 16, 2008**

OTHER PUBLICATIONS

(63) Continuation of application No. 29/304,787, filed on Mar. 7, 2008, now Pat. No. Des. 590,230, which is a continuation of application No. 29/287,310, filed on Jul. 23, 2007, now Pat. No. Des. 567,620, which is a continuation of application No. 29/257,020, filed on Mar. 29, 2006, now Pat. No. Des. 562,101.

FIG. 1 is a perspective illustration, from the front and left side, of a demolition tool according to our design;

FIG. 2 is a side elevational view thereof from the left side;

FIG. 3 is a top plan view thereof;

FIG. 4 is a front elevational view thereof;

FIG. 5 is a side elevational view thereof from the right side;

FIG. 6 is a bottom plan view thereof; and,

FIG. 7 is a back elevational view thereof.

The broken line showing of portions and features is included for the purpose of illustrating unclaimed subject matter and forms no part of the claimed design.

1 Claim, 7 Drawing Sheets
